UNITED STATES PATENT OFFICE.

GEORGE A. YANOCHEWSKI, OF CHICAGO, ILLINOIS, ASSIGNOR TO AUTOMATIC ELECTRIC COMPANY, OF CHICAGO, ILLINOIS, A CORPORATION OF ILLINOIS.

AUTOMATIC TELEPHONE SYSTEM.

1,347,069.

Specification of Letters Patent. Patented July 20, 1920.

Application filed April 10, 1916. Serial No. 90,047.

To all whom it may concern:

Be it known that I, GEORGE A. YANOCHEWSKI, a citizen of the United States of America, and a resident of Chicago, county of Cook, and State of Illinois, have invented certain new and useful Improvements in Automatic Telephone Systems, of which the following is a specification.

My invention relates to automatic telephone systems and more particularly to those automatic systems which are commonly known as, "two-wire", systems, so called by reason of the fact that the automatic switches are controlled over the two sides 10 of the line in series, exclusive of ground at the subscriber's station.

In systems of the above general character it has been the common practice to control the release and the switching of the local 20 circuits of the automatic switches through the medium of a combination of quick and slow acting relays. More specifically, a slow acting relay may be provided responsive to a prolonged interruption of the line circuit 25 to control the release, while a second slow acting relay may be provided responsive to a time interval between series of impulses to control the switching.

The object of my invention is to provide 30 an automatic system in which the control of the releasing and switching functions does not depend exclusively upon a time element, thereby avoiding to a considerable extent the use of slow acting relays.

The particular means employed in attaining 35 the foregoing ends and the operation thereof will be fully described hereinafter, reference being had to the accompanying drawings, in which Figures 1 and 2, when 40 taken in order with the lines at the ends thereof in alinement, represent diagrammatically a complete circuit connection between a calling substation A and a called substation A' in a system embodying the 45 principles of my invention. The said connection has been established through the medium of the individual line switch C, selector switch E, and connector H. Fig. 3 is 50 a detail of a portion of the dial mechanism.

Referring now to Fig. 1, the subscriber's 55 substation A may be of any suitable type and comprises the usual receiver 2, transmitter 3, ringer 4 and condenser 5. Being an automatic substation it is also provided with a suitable impulse sending device some-

what similar to that shown in British Patent No. 29,654 of 1910 to S. G. S. Dicker, except that two extra impulse springs are added, together with means for controlling the 60 same. The impulse sending device comprises a pair of impulse springs 6 and 7, and an auxiliary pair of impulse springs 9 and 10, which are assumed to be controlled through the medium of a finger hole dial 65 (not shown) in such a manner that the impulse springs 6 and 7 may be momentarily separated a number of times corresponding to the digit called, followed by a group of high speed impulses or interruptions transmitted by the impulse springs 9 and 10. These high speed impulses are similar to the impulses transmitted by the impulse springs 6 and 7 but are at a much greater speed, or in other words, they consist of one 70 or more interruptions or impulses at a high frequency, as compared to the impulses transmitted by the impulse springs 6 and 7. Referring to Fig. 3, it will be seen that to the rotatable portion 11 of the dial, there is 75 secured a pawl 12, one end of which is held in normal position against the pin 13 by a spring 14. When the dial is rotated in a clockwise direction (which is in a counter 80 clockwise direction as seen in Fig. 3), the pawl 12 strikes the spring 9 in such a manner as to tilt the said pawl downward, thus allowing it to pass the spring 9 without causing it to break contact with the spring 10. But when the dial is released and the 85 rotatable portion 11 rotates back to normal, one or more impulses are transmitted over the line conductors by means of impulse springs 6 and 7, then, just before the dial has returned to normal position, the pawl 12 engages the spring 9 and bends it downward 90 until the pawl 12 has passed beyond the said spring. When the pawl 12 releases the spring 9, the said spring vibrates for an instant and breaks contact several times 95 with spring 10, sending one or more quick or high frequency impulses.

The hook switch 16 in addition to controlling the usual hook switch springs 17, 18 and 19, also controls the springs 20, 21, 105 70 and 71. The springs 20 and 21 are constructed similar to the springs 9 and 10, that is, when the receiver is removed from the switch hook, the pawl 72 on arm 22 attached to the hook switch lever 16 operates to tilt downward and passes the springs 20 and 21 without separating their contact, 110

but when the receiver is placed upon the hook switch, the arm 22, in lowering, bends the spring 20 downward, after which and as soon as the spring 20 slides off the arm 5 22, a number of high speed impulses are sent over the line conductors similar to the impulses transmitted by the impulse springs 9 and 10. The springs 70 and 71 are also controlled by the switch hook 16 and operate 10 to short circuit the springs 6 and 7, and 9 and 10 when their contacts are closed. When the receiver is placed upon the receiver hook the springs 70 and 71 are adjusted to first close contact, thus shunting 15 the said impulse springs, then the springs 20 and 21 operate as herein described and lastly the springs 17 and 18 separate to open the line circuit.

The subscriber's individual switch C is 20 of the general type of line switch shown in British patent to R. W. James #26,301 of 1906, and similar to the type of switch shown in British patent to T. G. Martin #1419 of 1910, the circuits being slightly modified, 25 however. This line switch comprises, among other details, a plunger (not shown) attached to the end of a so-called plunger arm 23, which is controlled by the magnet 24. The magnet 24 comprises two windings, 30 namely, the pull-in winding 25 and the holding or cut-off winding 26. The winding 25 operates both the plunger arm 23 and the cut-off armature 27 while the winding 26 is only strong enough to operate the 35 armature 27 and to hold the plunger arm 23 in an operated position after it has once been operated by the pull-in winding 25. The circuit of the pull-in winding 25 is controlled by the line relay 28 and the 40 auxiliary relay 29, both of which I, preferably, make slow acting, that is, they are slow to deenergize after their energizing circuit has been broken. When the plunger arm 23 is operated, the plunger is forced 45 into a bank of contact springs, forcing the springs 30, 31, 32 and 33 into engagement with springs 34, 35, 36 and 37, respectively. Although only one set of springs (30-37) is shown, each line switch is provided with 50 a plurality of such sets, each set forming the terminal of a trunk line leading to a selector switch E. Each trunk line is connected in multiple to the corresponding springs of all the switches of the group 55 which is controlled by the master switch D.

The master switch D is of the same general type as that disclosed in British Patent #26,301 above referred to; being, however, of the particular type disclosed in said British Patent #1419 of 1910. The function 60 of the master switch, as is well known, is to maintain the plungers of all the idle line switches in position to engage the terminal of an idle trunk line.

65 The first selector E is of the same gen-

eral type of selector switch disclosed in the United States Letters Patent #815,331, granted March 13, 1906 to Keith, Erickson, and Erickson; except that the so-called side switch is dispensed with and the circuits are 70 modified in accordance with my invention to adapt the switch to operate in a system in which controlling impulses are delivered over the two sides of the line in series. Among other details, the selector E comprises 75 a bank of contacts arranged in horizontal rows or levels, which contacts are adapted to be engaged by a set of wipers 38, 39 and 40 carried upon a shaft (not shown) which has a vertical movement controlled by the vertical magnet 41 and a rotary movement controlled by the rotary magnet 42. The operations of various parts of the switch are controlled through the medium of the double wound line relay 43. 80 Means for permitting the switch to be restored to normal position is provided in the release magnet 44, which, upon energizing, withdraws the retaining double-dog from the shaft thereby allowing the shaft 90 and wipers to be restored to their normal position. The contacts 45 and 46 close only when the switch shaft has been raised one or more steps from its lowest position. The contact spring 47 (controlled by the armature 48 of line relay 43) is so constructed and adjusted as to follow up the spring 49 when the relay 43 is energized. Should one or more impulses be transmitted through the line relay 43, as ordinarily produced by 95 the operation of the impulse springs 6 and 7, the springs 47 and 49 will operate in unison and remain in contact, but should high speed impulses be transmitted to the line relay by means of the impulse springs 100 9 and 10 or the release springs 20 and 21, the springs 47 and 49 will be separated for an instant because the spring 47, by reason of the inertia of the weight at its extremity, is 105 unable to follow.

The connector switch H (Fig. 2) is of the general type of connector switch disclosed in United States Letters Patent #815,176 granted March 13, 1906, to Keith, Erickson, and Erickson; the circuits, however, being 110 modified in accordance with the same principles followed in the design of the selector E. Like the selector, the connector is provided with a shaft (not shown) carrying the wipers 55, 56, and 57, and controlled by the vertical magnet 53 and the rotary magnet 54. The usual side switch comprising the wipers 50, 51, 52, and 59 is controlled by the private magnet 58 in the usual and well known manner. The magnet 60 is the usual 115 release magnet. The relay 62 is the back bridge relay which furnishes talking battery to the called subscriber. The springs 63 and 64 controlled by the line relay 61 operate in the same manner as hereinbefore 120 125 130

described in the case of the springs 47 and 49 of the selector E. The contacts 65, 66, and 67 close only when the shaft has been raised one or more steps from its lowest position, while the contact 68 closes only when the shaft has been rotated one or more steps from its normal position. The relay 69 is the means through which ringing current is applied to the called line.

10 The substation shown at A' and the line switch C' are similar in all respects to the line switch C and the substation A.

For the purpose of supplying battery current for operating the apparatus at the 15 central exchange and for talking purposes, there is shown the battery B having its positive terminal grounded. At Q there is shown a busy signaling machine which provides a busy signal for application to the 20 calling line when the called line is in use.

Having given a general description of the apparatus and in order to give a clear understanding of the operation of the system, it will now be described in detail how 25 the calling subscriber at substation A may obtain connection with the subscriber at the called substation A'. We will assume that the number of the called substation is 220. Upon the removal of the receiver at 30 the substation A, a circuit is closed through the line relay 28 of line switch C. This circuit extends from ground G² through contact springs 73, conductor 75, to and through the substation A, conductor 76, springs 74 35 and the line relay 28 to battery B. The line relay 28, upon energizing, operates to close the circuit of the pull-in winding 25. This circuit extends from ground G' through the springs 66, springs 67 and 68, pull-in winding 25 and the springs 69 to battery B. The pull-in winding 25 operates to disconnect the line relay 28 from the line through the medium of cut-off armature 27, and to force the plunger into the bank of contacts 40 (30-37). The line relay 28 being slow acting, does not fall back immediately, however, but holds the plunger arm in an operated position until a holding ground is supplied to the holding winding 26 from 45 the selector E. The engagement of springs 30 and 33 with the springs 34 and 37, respectively, extends the subscriber's line to the line relay 43 of the selector E. The line relay 43 of the selector switch E is thereupon 50 energized, thereby closing a circuit through the relay 78, it being noted, that spring 47 follows spring 49 all the way so that springs 47, 49, and 77 come into electrical connection at the same time. The circuit for relay 78 55 extends from ground G³ through contact springs 77, 49, and 47', springs 79 and the relay 78 to the battery B. The relay 78, upon energizing, closes the above mentioned holding circuit through the cut-off winding 60 26 of line switch C. This circuit extends

from ground G⁴ through the springs 80, bank contact 35 and spring 31 and the said cut-off winding 26 to battery B. A guarding potential is supplied to the connector private bank contacts of the calling line by the 70 energization of relay 29. The energizing circuit for the relay 29 may be traced as a branch of the holding circuit from spring 31, through springs 81 and the relay 29 to battery B.

75

A further result of the energizing of line relay 43 is the closure of a circuit through the relay 82. This circuit extends from ground G⁵ through the springs 77 and 49, the upper winding of said relay 82 and the 80 springs 83 to battery B. The relay 82, upon energizing, forms a locking circuit for itself, extending from ground G⁵ through the springs 85, the lower winding of relay 82 and the springs 83 to battery B. A further 85 result of the energizing of relay 82 is to close a circuit through the relay 86. This circuit extends from ground G⁵ through the springs 88 and 87 and the said relay 86 to battery B. Further results of the energizing of relay 82 are the preparation of a 90 circuit for the vertical magnet 41 by closing the springs 89 and 90, and the opening of the circuit of the release magnet 44 at the springs 90 and 91. The apparatus is now 95 in readiness to receive impulses for the first digit.

If the calling subscriber should now replace his receiver upon the receiver hook the switch hook upon descending would cause 100 the springs 20 and 21 to operate in a hereinbefore mentioned manner to transmit one or more high speed interruptions or impulses. The relay 43 will vibrate its armature in response to the said impulses, with 105 the result that the springs 47 and 49 are separated for an instant at this time because the spring 47 has a slower natural period of vibration than the spring 49. It may be mentioned here that the rapid vibrations of 110 the line relay 43 do not affect the vertical magnet to any extent, for the closure of springs 97 is extremely short. The separation of the springs 47 and 49 for an instant allows the relay 94 to energize by removing the shunt around the said relay. The energizing circuit for the relay 94 extends from ground G⁵ through the springs 77 and 49, relay 94, and the relay 78 to battery B. The relay 94, upon energizing, permanently 115 opens the shunt from around itself at the springs 79 and opens the circuit of the relay 82 at springs 83, thus allowing the said relay 82 to deenergize; and as soon as the switch hook has separated the switch hook 120 springs 17 and 18 the line relay 43 deenergizes and opens the circuit of the relays 94 and 78. The relay 78, upon deenergizing, opens the circuit of the holding winding 26 of line switch C at the springs 80. The hold- 125 130

ing winding, upon deenergizing, permits the plunger arm of line switch C to return to normal.

We will assume, however, that the calling subscriber does not hang up at this time but instead operates his dial for the first digit 2 of the called number, whereby the substation impulse springs 6 and 7 are momentarily separated twice, followed by high speed impulses transmitted by the impulse springs 9 and 10. The line relay 43 responding to the two impulses sent by the impulse springs 6 and 7 operates to transmit two impulses of current through the vertical magnet 41. This circuit extends from ground G^s through contact springs 97, springs 98, springs 90 and 89 and the vertical magnet 41 to battery B. The vertical magnet receiving two impulses over this circuit operates to raise the shaft and wipers of selector E two steps to a position opposite the second row or level of bank contacts. The closure of the off-normal contact 46, which occurs when the selector shaft is raised, operates to close a locking circuit for the relay 86 over a path extending from ground G^s through the contact springs 80, springs 99, off-normal contact 46, springs 103 and 104 and the said relay 86 to battery B. The high speed interruptions at the springs 9 and 10 that follow the two impulses just transmitted by the impulse springs 6 and 7, cause the line relay 43 to vibrate quickly. As hereinbefore stated the result is that the springs 47 and 49 are separated for an instant thus allowing the relay 94 to energize over a previously traced circuit. The relay 94, upon energizing, opens the circuit of the relay 82 at the springs 83 and permanently removes the shunt from around itself at springs 79. The deenergizing of relay 82 closes a circuit through the rotary magnet 42 over the following path: ground G^s , contact springs 80, springs 99, contact 46, springs 103 and 104, springs 87 and 105, springs 101 and the rotary magnet 42 to battery B. The rotary magnet, upon energizing, rotates the wipers one step and, by separating the springs 99 and the springs 101, opens its own circuit and also the circuit of relay 86. If the first trunk line of the second level is idle, the relay 86 deenergizes immediately, but if this trunk line is busy, the private wiper 39 finds the contact with which it engages provided with a guarding ground potential, which is transmitted to the relay 86 through the springs 103 and 104, thereby preventing it from deenergizing. The rotary magnet, however, deenergizes when the springs 101 separate, regardless of whether the relay 86 remains energized or not. If the relay 86 remains energized, the circuit of the rotary magnet will be again closed as soon as the armature drops back far enough to close the

springs 101. The rotary magnet will, therefore, operate in a manner similar to that of a buzzer to advance the wipers step by step over the contacts until the non-guarded contact of an idle trunk line is reached by the wiper 39, whereupon the relay 86 deenergizes. The relay 86, upon deenergizing, whether after one or several operations of the rotary magnet, permanently breaks the circuit of the magnet 42 and closes the circuit of the switching relay 106. The circuit through said relay 106 extends from ground G^s through the contact springs 80, springs 99, contact 46, springs 103 and 102 and the switching relay 106 to battery B. The relay 106, upon energizing, extends the line connection through the wipers 38 and 40 to the line relay 61 of connector H and disconnects the line relay 43 from the said calling line. 85

The line relay 61, upon energizing, closes a circuit through the relay 110. This circuit extends from ground G^s through the springs 111 and 64, lower winding of relay 110, springs 112, springs 114, springs 115, and the side switch wiper 59 (in first position) to battery B. The relay 110, upon energizing, closes a locking circuit for itself through the springs 116, and prepares a circuit for the vertical magnet by bringing the springs 118 and 119 into engagement. A further result of the energization of the line relay 61 is the closure of a circuit through the relay 120. This circuit extends from ground G^s through the springs 111, 64, and 63, springs 113 and the relay 120 to battery B. The relay 120, upon energizing, supplies a holding ground to the trunk release conductor 108 to hold the relay 106 of selector E and winding 26 of line switch C energized. This circuit extends from ground G^s through the springs 121, springs 122, conductor 108, wiper 39 to wire junction 124, where the circuit divides, one branch extending through the springs 103 and 102 and the relay 106 to battery B, and the other branch extending from point 124 through the off-normal contact 46, springs 99, bank contact 35, springs 31 and the holding winding 26 to battery B. 11

If the calling subscriber should now replace his receiver upon the receiver hook the switch hook upon descending would cause the springs 20 and 21 to operate in a hereinbefore mentioned manner to transmit one or more high speed interruptions or impulses. The line relay 61 will respond to the said impulses and as hereinbefore stated the result is that the springs 63 and 64 are separated for an instant at this time because the spring 63 has a slower natural period of vibration than the spring 64. The separation of the springs 63 and 64 for an instant allows the relay 125 to energize by removing the shunt from around the said relay. The energiz- 12 13

ing circuit for relay 125 extends from ground G^8 through the springs 111 and 64, relay 125, and the relay 120 to battery B. The relay 125, upon energizing, opens the shunt from around itself at the springs 113, 5 opens the circuit of relay 110 at springs 112, and closes a circuit through the private magnet 58 over a circuit extending from ground G^{11} through the contact springs 127, 128, and 129, magnet 58 and the side switch wiper 59 (in first position) to battery B. As soon as the receiver hook has descended far enough to open the circuit of line relay 61, the said relay will deenergize. The line 10 relay, upon deenergizing, opens the circuit of relays 125 and 120 at springs 64 and 111. The relay 125, upon deenergizing, opens the circuit of the private magnet 58, at the springs 127, 128 and 129; but the private 15 magnet, upon deenergizing, does not trip the side switch to second position as the side switch cannot advance to second position until the switch shaft has been raised one or 20 more steps from its lowest position as shown in the patents above referred to. The relay 120, upon deenergizing, removes the ground from the trunk release conductor 108 at the springs 121, thus allowing the relay 106 of selector E and holding coil 26 25 of line switch C to deenergize. The line switch C releases in the hereinbefore mentioned manner. The relay 106, upon deenergizing, closes a circuit through the release magnet 44. This circuit extends from ground G^6 through the springs 97, springs 98, 30 springs 90 and 91, release magnet 44 and the off-normal contact 45 to battery B. The release magnet, upon energizing, withdraws the retaining double-dog from the shaft and 35 the switch releases in a well known manner. 40

Assuming that the calling subscriber did not replace his receiver at this time, but that he operates his dial for the second digit 2 of the called number, the substation impulse springs 6 and 7 are separated twice, followed 45 by high speed impulses transmitted by the impulse springs 9 and 10. The line relay 61 responding to the two impulses sent by the impulse springs 6 and 7 operates to transmit 50 two impulses through the vertical magnet 53. This circuit extends from ground G^{13} through the springs 130, springs 118 and 119, the vertical magnet 53, and the side switch wiper 51 (in first position) to battery B. The vertical magnet, upon receiving 55 the two impulses over this circuit, operates to raise the shaft and wipers two steps to a position opposite the second row or level of bank contacts. The high speed 60 interruptions that follow the two impulses just transmitted by the impulses springs 6 and 7 cause the line relay 61 to vibrate quickly. As hereinbefore stated the result is that the springs 63 and 64 are separated 65 for an instant, thus allowing the relay 125 to energize over a hereinbefore traced circuit. The relay 125, upon energizing, closes a circuit through the private magnet 58 and opens the circuit of the relay 110. The relay 110, upon deenergizing, shunts out the 70 relay 125 over a circuit extending from ground G^8 through the springs 111, 64 and 63, off-normal contact 65, and springs 131 to one terminal of relay 125, the other terminal being connected to ground G^8 over a 75 hereinbefore traced circuit. The relay 125, upon deenergizing, causes the private magnet 58 to advance the side switch to second position and again closes the circuit of relay 110 at the springs 112. The springs 113 80 and 112 of relay 125 are so adjusted that the relay 125, upon deenergizing, again places a shunt around itself before the circuit of relay 110 is closed. The side switch wiper 51 moving from first to second position transfers the battery connection from the vertical magnet 53 to the rotary magnet 54. 85

The apparatus is now in readiness to receive impulses for the third digit 0. If the 90 calling subscriber should now replace his receiver hook, the springs 20 and 21 will operate in a hereinbefore described manner to transmit one or more high speed impulses which cause the line relay 61 to respond to 95 said impulses and to operate relays 125 and 110, as hereinbefore described. The relay 125 operates to close a circuit through the private magnet and the release magnet 60. The private magnet is unable to advance 100 the side switch from second to third position, because, as is well known, the side switch is mechanically locked in second position until the switch shaft has been rotated one or more steps from normal. The 105 circuit through the release magnet extends from ground G^{11} through the springs 127 and 128, side switch wiper 50 in second position, rotary off-normal contact 68, release magnet 60 and the vertical off-normal 110 contact 67 to battery B. The release magnet, upon energizing, closes a locking circuit for itself through the springs 134, and off-normal contact 66 to G^{16} and restores the switch shaft and side switch wipers to normal position and its own circuit is broken at the contacts 67 and 66 when the switch shaft reaches its lowest position. The relay 120, being slow acting, will deenergize a short time after its energizing circuit is 120 broken by the line relay 61. The relay 120, upon deenergizing, removes the ground from the trunk release conductor 108, allowing the selector E and line switch C to release as hereinbefore described. 125

Assuming that the calling subscriber did not replace his receiver upon the receiver hook, but that he operates his dial for the last digit 0, the substation impulse springs 6 and 7 are separated ten times followed by 130

high speed impulses transmitted by the impulse springs 9 and 10. The line relay 61 responding to the ten impulses sent by the impulse springs 6 and 7 operates to transmit 5 ten impulses through the rotary magnet 54. This circuit extends from ground G^{13} through the springs 130, springs 118 and 119, rotary magnet 54, and the side switch wiper 51 (in second position) to battery B. The rotary magnet, responding to the ten impulses transmitted by the line relay 61, operates to rotate the line wipers onto the contacts of the desired line. The high speed impulses which follow cause the line 10 relay 61 to operate to separate the springs 63 and 64 for an instant, thereby allowing the relay 125 to operate to close a circuit through the private magnet 58 and to open the circuit of the relay 110 at the springs 15 112. The relay 110, upon deenergizing, again places a shunt around the relay 125, thus causing the relay 125 to deenergize, which causes the private magnet to deenergize and advance the side switch to third 20 position. The circuit of the relay 110 is again closed at the springs 112 when the relay 125 deenergizes but the said relay does not energize at this time as its circuit was opened at the side switch wiper 59 when it 25 passed from second to third position. The opening of the rotary off-normal springs 68 prevents the release magnet 60 from being energized when the relay 125 is energized at this time. The side switch wiper 30 52, upon passing to third position closes a circuit through the cut-off winding 136 of line switch C, and the relay 138 of connector H. A further result of the passing of side switch wiper 52 to third position, is 35 the placing of a guarding potential upon the multiple bank contacts of the called line. The energization of the relay 138 completes the line connection from the calling to the called subscriber's line. The side 40 switch wiper 51 upon passing from second to third position closes a circuit through the ringer relay 69. This circuit extends from ground G^{15} through the interrupter 139, ringer relay 69, springs 140 and the side switch wiper 51 (in third position) to battery B. The ringer relay 69, upon energizing, disconnects the calling line from the 45 called line and bridges the ringing current generator R across the called line. The ringer relay 69 is energized intermittently through the medium of the interrupter 139. Upon the response of the called subscriber his line is provided with talking battery through the windings of the back bridge 50 relay 62, which relay, upon energizing, closes a circuit through the ringer cut-off relay 142. This circuit extends from ground G^{16} through off-normal contact 66, springs 143, (relay 142 and the side switch wiper 55 51 (in third position) to battery B. The

relay 142, upon energizing, opens the circuit of the ringer relay 69 at springs 140 and closes a locking circuit for itself through the springs 144 independent of the springs 143.

A complete talking connection has now been established and the subscribers may converse without further effort. The transmitter at the calling substation is supplied with talking current through the windings 70 of the double-wound relay 61, while the transmitter at the called substation is supplied with talking current through the windings of the double-wound relay 62. The path for voice currents has been drawn 75 80 in heavy lines and will be apparent without further explanation.

After the conversation is completed, the connection is released by the hanging up of the receiver at the calling substation in the 85 following manner: The connector is released by the opening of the switch hook springs 17 and 18, which opens the circuit of the connector line relay 61. The line relay 61, upon deenergizing, closes a circuit through 90 the release magnet 60 and opens the circuit of the relay 120 at springs 111 and 64. The circuit for the release magnet extends from ground G^{13} through the springs 130, springs 118 and 117, release magnet 60 and the off-normal contact 67 to battery B. Upon the closure of the above circuit, the connector releases in the manner previously described. The relay 120, upon deenergizing, removes 95 the holding ground G^9 from the release conductor 108, allowing the selector E and line switch C to release as hereinbefore described.

It having been explained how one subscriber establishes connection with another subscriber and releases the same, it will now 100 be explained how a connection is prevented from being made with a busy line, how the calling automatic switches are released, and how the calling subscriber receives a busy signal from his own individual line switch.

If the called number is busy there will be a guarding potential upon the connector private bank contact, just as explained in connection with line switch C. The connector private wiper 56, upon engaging this guarding contact and when the private magnet 58 energizes, a circuit is closed through the busy relay 145. This circuit extends from ground 115 upon the private bank contact through the wiper 56, side switch wiper 52 (in second 120 position), busy relay 145, and the springs 146 of private magnet 58, to battery B. The relay 145, upon energizing, closes a locking circuit for itself through the contacts 147 independent of the private magnet 58, removes the ground from the release conductor 108 at springs 122, and opens the circuit of relay 110 at springs 114. The removal of the ground from the said conductor 108 causes 125 the plunger of the line switch C to be with- 130

drawn from its bank of contacts and the selector E to be released as hereinbefore described. The cut-off arm 27 and plunger arm 28 dropping back allow the circuit of the line relay 28 to be closed. The relay 28, upon energizing, closes a locking circuit through the relay 29, which being slow acting has not deenergized. The relay 29 maintains the circuit of the pull-in winding 25 open at the springs 68 and 67. A further result of the energization of the line relay 28 is the supplying of a busy tone from the machine Q to the calling line through the contact of its springs 148. The opening of 15 the line circuit of the connector H at the bank springs 30, and 33 causes the line relay 61 to deenergize. The line relay 61, upon deenergizing, causes the connector H to release as hereinbefore described. The calling 20 scribe upon receiving the busy signal replaces his receiver upon the receiver hook and releases relays 28 and 29 of the line switch C, whereupon all the apparatus will have been returned to normal.

25 It will be seen from the foregoing that my invention provides an automatic telephone system, in which the local, "switching," at the various automatic switches is accomplished entirely through the medium of a device responsive to high frequency impulses while irresponsible to the preceding operating impulses; and it will be seen, furthermore, that at certain times the release of the 30 automatic switches is brought about directly or indirectly in response to similar high frequency impulses transmitted by the subscriber's switch hook.

While I have illustrated and described herein a certain particular embodiment of 40 my invention, I do not wish to be held to the exact form shown, for modifications will no doubt be devised by persons skilled in the art. I desire, therefore, to include and have 45 protected by Letters Patent all forms and modifications of my invention which may come within the scope of the appended claims.

What I claim as my invention is:

1. In a telephone system, an automatic 50 progressively movable switch, a controlling circuit for said switch including the two sides of a calling line in series, an operating magnet and a release magnet for said switch, means for transmitting a plurality 55 of impulses of one character over said controlling circuit to control said operating magnet, and means for transmitting a plurality of impulses of a different character over said controlling circuit to control said 60 release magnet.

2. In a telephone system, an automatic 65 progressively movable switch, a controlling circuit for said switch, an operating magnet and a release magnet for said switch,

means for transmitting impulses of low and 65 high frequency over said circuit, a relay in said switch responsive to said low frequency impulses for controlling said operating magnet, and a relay in said switch responsive to said high frequency impulses for 70 controlling said release magnet.

3. In a telephone system, an automatic progressively movable switch, a controlling circuit for said switch, an operating magnet and a release magnet for said switch, 75 means for transmitting low and high frequency impulses over said circuit, a relay in said switch for controlling said release magnet, and a line relay in said switch responsive to said low frequency impulses for 80 controlling said operating magnet and responsive to said high frequency impulses for operating said first relay to release said switch.

4. In a telephone system, a line terminating 85 in an automatic progressively movable switch, means at the substation on said line for transmitting groups of operating impulses of one frequency and a group of releasing impulses of a different frequency to 90 said switch over said line, said switch provided with operating means responsive to said group of operating impulses, and releasing means responsive to said group of releasing impulses. 95

5. In a telephone system, a substation telephone instrument and a line therefor extending to a central exchange, an automatic switch, means at the exchange for making said switch accessible to said line, means in 100 said instrument for sending directive impulses over said line to operate said switch, means controlled by the receiver hook of said telephone instrument for sending a group of high frequency impulses over said 105 line, and means responsive to said last impulses for releasing said switch.

6. In a telephone system, an automatic progressively movable switch provided with operating means and releasing means, and 110 a common controlling circuit therefor, said means separately responsive to impulses of different frequency transmitted over said controlling circuit.

7. In a telephone system, a calling subscriber's line, means including an automatic switch for extending said line into connection with a called line, means at the substation on the calling line for producing long and short interruptions of the line circuit 115 120 for controlling said switch, operating mechanism in said switch responsive to said long interruptions, and release mechanism in said switch responsive to said short interruptions. 125

Signed by me at Chicago, Cook county, State of Illinois, this 5th day of April, 1916.

GEORGE A. YANÓCHOWSKI.
